UNITED STATES PATENT OFFICE.

ALBERT R. JAMES, OF HAMILTON, ONTARIO, CANADA, ASSIGNOR TO THE
SEAMLESS SHOE CRIMPING COMPANY, OF PORTLAND, MAINE.

STRETCHING AND CRIMPING MACHINE.

SPECIFICATION forming part of Letters Patent No. 373,775, dated November 22, 1887.

Application filed August 4, 1887. Serial No. 246,112. (No model.)

To all whom it may concern:

Be it known that I, ALBERT R. JAMES, of Hamilton, county of Wentworth, Ontario, Canada, have invented an Improvement in 5 Upper Stretching and Crimping Machines, of which the following description, in connection with the accompanying drawings, is a specification, like letters on the drawings representing like parts.

10 This invention has for its object the production of a machine by which to properly stretch the upper of a shoe preparatory to applying it to a last to receive a slug, the stretching operation as practiced in my invention being 15 substantially a crimping operation.

My invention is herein shown in connection with a seamless upper, substantially such as shown in United States patent to Marshall, No. 346,055, dated July 20, 1886, the said upper 20 perhaps having been previously crimped by mechanism substantially such as represented in patent of the United States granted to me, No. 363,521, dated May 24, 1887, or by any other similar mechanism.

25 My improved mechanism herein shown contains a toe, a heel or quarter, and an intermediate standard made movable relatively each to the other to permit the upper placed thereon and clamped to the toe and intermediate 30 standard to be stretched. As herein shown, the quarter or heel standard and the intermediate standard are made movable, the quarter or heel standard being under the control of a standard-moving device, (shown as a lever,) 35 which has co-operating with it a locking device to retain the heel or quarter standard in its adjusted position.

40 My improved machine also contains a wiper for smoothing the quarter, to be described.

Instead of the locking device herein shown, I may use any other usual or well-known locking device, operated either by teeth or by friction.

45 Figure 1, in side elevation, represents my improved machine, the said figure showing an upper as stretched and as being smooth at the quarter, the upper being broken out to show part of the clamping-surfaces within it. Fig. 50 2 is a left-hand end view of the machine shown

in Fig. 1. Fig. 3 is a section in the line x, Fig. 1. Fig. 4 represents the intermediate standard and its clamp, with a small portion of the toe-standard above it, the view being to the right of the dotted line x', the full lines, 55 Fig. 4, showing the clamp closed upon the upper, the dotted lines showing the parts when the clamp is not so closed; and Fig. 5 is an under side view of the standard-moving device and part of its locking device removed 60 from the machine.

The base A of the machine has erected upon it a toe-standard, B, which, as herein shown, is supposed to be fixed to the said base, the said standard having preferably a horizontally-extended arm, B', to support the vamp of the upper from its toe to the central slit or opening therein, through which the foot is to pass when putting on the shoe. The heel or "quarter" standard C, as I shall call it, as well 65 as the intermediate standard, D, have, as herein, like feet, as C', preferably of dovetailed shape in cross-section, which fit and slide in correspondingly-shaped guideways of the base A. The quarter-standard C has as 70 its moving device a lever, E, having its fulcrum at E', the said lever being extended through a slot or opening in the said quarter-standard and being provided with a secondary lever, a', upon which are pivoted loosely two clamp- 75 blocks, a⁵ a⁶, having, respectively, concaved and convexed faces to fit against a curved ledge, as a', erected upon the base A, the said secondary lever being normally acted upon by a spring, a*, which retains the clamping-blocks 80 in position to bite the rest-ledge. The handle of the secondary lever is prolonged, so as to be grasped by the operator at the same time that he grasps the moving device E, the grasping of the moving device E effecting the turning 85 of the secondary lever in the direction to release the clamps, so that the moving device may be moved without interference; but as soon as the handle is released the clamps become effective to lock the moving device in 90 position. The quarter-standard C has extended backwardly from it an arm, C', slotted, as shown at c, for the reception of a bolt, as 2, which bolt is also extended through depending ears e of a carriage or slide-block, e', upon 95 100

which is pivoted by a pin, e^2 , two wipers, e^3 , each wiper having attached to it a handle, e^4 , the said wipers being so pivoted that downward pressure upon the handles e^4 will enable 5 the operator to cause the inturned lower edges of the wipers (see Fig. 3) to act with more or less force against the upper (herein marked u) to smooth or wipe the same down in the direction of the dotted line x^3 , downward movement of the wipers removing from the upper any wrinkles which may be formed therein and fitting the quarter of the upper close to the quarter-standard.

Each wiper has a pin or stud, as 4 , to which 15 is connected a spiral or other suitable spring, 5 , the opposite end of each of the said springs being attached to a pin or stud, 7 , the said pins being extended from opposite sides of a block, 8 , through slots 10 in the wipers, the 20 block rising and falling with the wipers and being held by the springs against the quarter of the upper immediately at the rear edge of the quarter-standard C . When the operator starts to move the quarter-standard C away 25 from the toe-standard B , the stud 2 will preferably stand in the left-hand end of the slot c , and in such condition the wipers will be moved in unison with the standard C . As soon, however, as the standard C has been pulled away 30 from the standard B sufficiently to stretch the upper as much as desired, then the standard C is locked, and the operator, by the handles e^4 , pushes forward the wipers until their front ends come against the quarter of the upper 35 near the upper portion thereof, and thereafter, as the operator pushes the wipers forward, holding each of them pressed firmly against the quarter of the upper at one side of the standard C , he at the same time pushes the 40 wipers downward until they pass from the lower edge of the upper. The intermediate standard, D , has pivoted upon it at d (see Fig. 4) two jaws, d' , the upper ends of which will in practice be serrated to engage the lower edge 45 of vamp and clamp it against opposite sides of the intermediate standard, D , the said standard at its opposite sides in line with the upper ends of the jaws being also preferably suitably roughened or toothed to co-operate with the 50 jaws, in order that the lower edge of the vamp may be very firmly held while the vamp is being stretched by the movement of the standard C . The toe of the upper, folded about the top of the toe-standard B , is also toothed or 55 corrugated, as at b , and the toe of the upper is embraced between like jaws b' , pivoted together at b^2 , (see Fig. 2,) the said jaws serving as a clamp to firmly clamp the toe of the upper to the toe-standard B .

60 One of the jaws d' has screwed or otherwise connected to it one end of a rod or stud, d^3 , and the said stud, extended through a hole in the standard D and through the other jaw, b' , as shown in Fig. 4, has pivoted upon it by a 65 pivot, as d^4 , (shown by dotted lines, Fig. 4,) a lever, d^5 , it having a cam-shaped head, or a head shaped substantially as the head b^6 of the

lever b^5 , pivoted at b^4 on a stud, as b^2 , extended loosely through one of the jaws b' and connected positively to the other jaw. The stud d^3 , as well as the stud b^3 , between the jaws d' and b' are surrounded by suitable spiral springs, which act normally to keep the jaws of the said clamps opened; but by turning the cam-headed levers d^5 or b^5 the said jaws may 75 be made to approach each other and clamp the upper laid over through the standard D or B , the clamps or jaws remaining closed as long as desired. As the standard C in the slot in the seamless folded upper is moved 80 away from the standard B , it acts at first upon the leather at the end of the slot farthest from the extension B' , and by the time the standard C reaches the position Fig. 1 the portion of the leather adjacent to the slit has 85 been stretched sufficiently to enable the material of the upper between the outer end of the slit and the rear end of the seamless blank to lie close to the outer edge of the standard C , the latter edge serving to shape the rear end 90 of the seamless vamp to constitute a seamless counter. As the seamless upper, held at its toe by the clamps b' , is being elongated, as described, the extension B' and clamps d' act to prevent the contraction of the vamp of the 95 upper in width, thus compelling the standard C in its movement to take all the leather required for its movement from the seamless blank between the clamp d' and the end of the blank. During this stretching operation the 100 standard D sometimes has imparted to it a slight horizontal movement. This is provided for by mounting the foot of the standard D loosely in guideways of the base A .

I do not desire to limit my invention to 105 stretching simply uppers which are seamless.

I claim--

1. The combination, with the toe-standard and clamp to hold the toe of an upper, of a heel or quarter standard extended through the 110 foot-receiving opening of the upper and with means for moving one of the said standards with relation to the other to stretch the said upper between its heel and toe covering portions, substantially as described.

115

2. The toe-standard, a clamp to clamp and hold the toe of the upper, a quarter-standard to enter the foot-receiving opening of the upper, and an intermediate standard and clamp to hold the jaws of the upper between the toe 120 and heel covering portions therefor, and with means to change the relative positions of the said parts to effect the stretching of the upper in the direction of its length and also of its width, as set forth.

125

3. The toe-standard and the quarter-standard, combined with the standard-moving device and locking device therefor, substantially as described.

4. The toe-standard, its holding-clamp, and the quarter-standard, combined with a wiper to wipe the stretched quarter upon and closely against the quarter-standard, substantially as described.

130

5. The quarter-standard and a guide, C², combined with a pair of wipers, substantially as described, adapted to be pushed forward over and down upon the quarter from its upper 5 per toward its lower edge, for the purposes set forth.

6. That improvement in the art or method of stretching and crimping a seamless slotted blank for the production of a shoe-upper which 10 consists in folding the upper longitudinally, holding the vamp at the toe and back from the toe, then stretching the seamless vamp by a direct pull applied within the slit at the top of the heel portion of the seamless upper held 15 at its toe, and pulling the said blank until the

material in the line of the slit is stretched in excess of the outer edge of the blank sufficiently to bring the portion of the seamless vamp between the outer end of the slot therein and the outer end of the blank in proper 20 position to serve as the counter for the upper, all substantially as shown and described.

In testimony whereof I have signed my name to this specification in the presence of two subscribing witnesses.

ALBERT R. JAMES.
